CLOTH BAG CLEANER

William H. Bagby, Minneapolis, Minn., assignor
to General Mills, Inc., a corporation of Delaware

Application September 7, 1944, Serial No. 553,098

7 Claims. (Cl. 223—43)

1

This invention relates to an apparatus for cleaning cloth bags.

Heretofore it has been customary to manually hold each bag to be cleaned suspended under a vacuum tube which sucks the bag up into the tube turning it inside out and then pulling it out and again reversing it by again holding it suspended beneath the tube. As the air rushes through the cloth of the bag, particularly when the bag is held inside out, it loosens and removes much of the material adhering to the bag and carries it away. More is loosened and removed when the bag is again turned right side out by holding it under the tube and air passes from what is normally the inside of the bag to the outside.

An object of the invention is to provide a more speedy and efficient means for cleaning cloth bags, particularly those which have been emptied of flour, feed, cement and the like, where the material packed has a tendency to adhere to the bag.

This and other objects, as will hereinafter appear, are accomplished by this invention which is fully described in the following specification and shown in the accompanying drawings in which

Figure 1 is a top plan view of an embodiment of the invention;

Fig. 2 is a front elevation of the same;

Fig. 3 is a diagrammatic view of the upper portion of the machine shown in vertical section;

Fig. 4 is an enlarged partial end view of the upper portion of the machine;

Fig. 5 is an enlarged partial perspective of the hollow frame showing the grippers open for the reception of one side of the bag;

Fig. 6 is an enlarged partial perspective showing gripper frames beneath the two tubes shown in full line, while one of the frames is shown in dotted line passing from a position beneath one of the tubes to a position beneath the other tube;

Fig. 7 is a partial perspective of one of the frames with the grippers open for the reception of the bag;

Fig. 8 is a similar view of the frame with the grippers open for the release of the bag;

Fig. 9 is a partial enlarged section on the line 9—9 of Fig. 7;

Fig. 10 is a partial perspective of the lower right-hand corner of the frame as shown in Fig. 2 showing particularly the guides for guiding the frame around the corner;

Fig. 11 is a partial enlarged section of one side of the gripper frame; and

2

Figs. 12 and 13 are sections on the lines 12—12 and 13—13 of Fig. 11.

The embodiment illustrated comprises a main frame 20 supported on legs 21 and carrying suitable bearings in which are journaled shafts 22, 23, 24 and 25 at the four corners of a rectangle. Each shaft carries two spaced sprockets as 26, 27, 28 and 29. Continuous conveyor chains 30, 31 pass around these sprockets and are driven by a pulley 32 on the head shaft 23.

Each chain slides on guide strip 33 carried on top rails 34 and carries registering bearing blocks 35, 36 (Fig. 7) and in these are journaled short hollow shafts 40, 41 each secured to a U-shaped frame member 42, 43 (Fig. 10) respectively. These are adjustably secured together by means of suitable bolts 44 at each side of the frame.

Within the hollow shaft 40 is slidably mounted a rod 50 which carries a collar 51 against which bears a spring 52 urging the rod outwardly. This rod at its inner end carries a gripping bar 55 which has teeth 56 meshing with corresponding indentations 57 in an extension 58 secured to the inner face of the frame member 42 (Fig. 11). The shaft 40 has a screw engaging a keyway in the rod 50 as shown in Fig. 12 to prevent rotation of the bar 55.

The hollow shaft 41 carries a similar rod 50' and gripping bar as that shown in Fig. 11 and these rods extend beyond the ends of the shafts 40 and 41 so as to engage and be pressed inwardly by lateral guides 61, 62, as shown in Fig. 7. When so pressed in, the gripping bar 55 is forced in so as to permit an upper edge of the bag B to be inserted between the open jaws, as shown in Fig. 5. For this purpose, openings 65 are provided in the members 66.

A number of these gripper frames are provided on the continuous chains, as shown in Fig. 2, and these are preferably but not necessarily spaced apart a distance equal to the distance between stations, as shown in Fig. 2, and which will later be described. Where the chains are run intermittently the frames should be spaced the same as the stations.

Referring to Figs. 5 and 7 the operator picks up a bag by the top and inserts a portion of the top between the open far grippers while they are held open by the guide 62. The operator holds the bag between the grippers until the rod 50' runs off the end of the guide 62. It will be observed that the guide 61 then holds the rod 50 depressed for some time after the rod 50' has been released. During this time the operator grasps the open top of the bag and inserts it between

the near grippers, holding the bag until the rod 50 runs off the end of the guide 61. The bag is then firmly gripped.

The bag then continues to move to the left from station 1, as shown in Fig. 3, and at the point marked station 2 (Sta. 2) the frame passes beneath the tube 70 which is connected to an exhauster or other source of low vacuum. This tube is preferably larger than the bags to be cleaned and is provided with a hollow cylindrical basket which is made up of vertical bars 71 reinforced by circular hoops 72. This structure is brazed or welded at the bottom to the tube and at the top to a screen-grid structure 73. An inspection door 74 is located above said screen grid. This basket permits the cleaning of bags which on occasion may be larger in diameter than the tube 70.

When the frame passes beneath the tube the bag is drawn up through the frame and into the tube, thereby turning the bag inside out with considerable violence which assists materially in shaking loose dust and powdered material within the bag and even breaking loose some of the material which has adhered to the bag. When the bag is gripped at station 1, as shown in Fig. 2, it depends from the gripping frame, assuming the position B₁. When the frame is immediately under the tube 70 the bag is drawn up into the position B₂ within the tube by the ingoing air. As the frame F continues to move, the inrushing air tends to retain the bag in the tube and it assumes a position like B₃ (Fig. 3) as it is slowly drawn out of the tube. At the same time the frame F is caused to rotate in a clockwise direction and engages a cross-bar 75 which insures the frame rocking over as it passes beneath this bar. The bag now completely released from the tube 70 drops to the dotted line position B₄, the bag now being turned inside out. The weight of the bag dropping from the tube is often sufficient to rock over the frame to inverted position without the aid of the cross bar.

As the frame continues on it passes beneath the suction tube 80 which may be identical with the tube 70. Here again the bag is drawn up inside this tube and again reversed so that in the mid-position B₅ it is again right side out.

As the frame now continues it is drawn out from the tube 80, assuming the position B₆, as shown at station 3 of Fig. 3. A bar 85 similar to the bar 75 again insures the frame turning as the bag leaves the tube 80. The frame and bag then drop to the position B₇ in which position the rods 50, engage releasing slides 90, 91 (Fig. 1) which press the rods in, thereby releasing the bag grippers and the bag B₈ then drops into a suitable chute 92.

Each shaft 40 is provided with a pair of set collars 94 secured by set screws which permit of adjustment of the shaft to accommodate bags of different sizes.

Referring to Fig. 2 a bottom guide rail 95 prevents the frames F from turning. End guide rails 96, 97 guide the frames around the shafts 22, etc. and around the ends of the machine, keeping them parallel to the chains. Guides 98 are located at station 1 and guides 99 are placed beneath stations 2 and 3 to insure the frames remaining horizontal.

While I have shown and described but a single embodiment of my invention, it is to be understood that it is capable of many modifications. Changes, therefore, may be made which do not

depart from the spirit and scope of my invention as disclosed in the appended claims.

I claim as my invention:

1. In a bag cleaning machine a tube maintained under a partial vacuum and open at one end, a series of open frames through each of which a bag may pass, each frame having grippers thereon for gripping the open top of a bag to be cleaned, a continuous chain conveyor for moving each frame beneath the open end of the tube while a depending bag is gripped therebeneath so that the suction in the tube will draw the bag through the open frame and into the tube as it passes thereunder thereby turning the bag inside out, the frame being centrally pivoted at its sides on said chain conveyor so that the frame rotates through half a revolution as the bag is drawn from the tube and again depends from the frame, a second tube beyond the first tube and similarly exhausted to reverse the bag again as the conveyor chain moves the inverted frame to a position thereunder and further clean it by the passage of air therethrough, and means beyond the second tube for releasing the bag after it has been moved from beneath the second tube by the conveyor means.

2. In a bag cleaning machine, a tube maintained under a partial vacuum and open at one end, an open frame through which a bag may pass having grippers thereon for gripping the open top of a bag to be cleaned, a continuous chain conveyor for moving the frame beneath the open end of the tube while a depending bag is gripped therebeneath so that the suction in the tube will draw the bag through the open frame and into the tube thereby turning the bag inside out through the hollow frame, the frame being centrally pivoted at its sides on said chain conveyor so that the frame rotates through half a revolution as the bag is drawn from the tube and again depends from the frame, a second tube beyond the first tube and similarly exhausted to reverse the bag again and further clean it by the passage of air therethrough, and means beyond the second tube for releasing the bag after it has been moved from beneath the second tube by the conveyor means.

3. In a bag cleaning machine, a tube maintained under a partial vacuum and open at one end, an open frame through which a bag may pass having grippers thereon for gripping the open top of a bag to be cleaned, a continuous chain conveyor for moving the frame beneath the open end of the tube while a depending bag is gripped therebeneath so that the suction in the tube will draw the bag through the open frame and into the tube thereby turning the bag inside out, the frame being centrally pivoted at its sides and said chain conveyor so that the frame rotates to inverted position as the bag is drawn out by the moving conveyor and again depends from the frame, a second tube beyond the first tube and similarly exhausted to reverse the bag again as the conveyor chain moves the inverted frame thereunder and further clean it by the passage of air therethrough, and laterally extending members movably carried by said frames adapted to engage fixed elements in the machine to cause the grippers to open to receive a bag at the head end of the machine and to release the bag at the tail end.

4. In a bag cleaning machine, a vertical tube maintained under a partial vacuum and open at the bottom, a plurality of open frames through each of which a bag may pass, each frame hav-

ing grippers thereon for gripping the open top of a bag to be cleaned, means including two spaced continuous chains on which the frames are pivoted for rotation about horizontal axes, said means moving the frames beneath the tube while a depending bag is gripped by each frame therebeneath so that the suction in the tube will draw the bag through its open frame and into the tube thereby turning the bag inside out, a similar second tube for again cleaning and reversing the bag, and means for releasing the bag after it emerges from the second tube.

5. In a bag cleaning machine, a cleaning tube for drawing foreign matter from a bag, an open frame through which a bag may pass having grippers with a movable jaw on the near and far side for gripping the open top of a bag to be cleaned, stationary cam surfaces parallel to the path of travel of the frame and adjacent the near and far side of the frame opening the movable jaw to open the grippers as the frame is moved past, the parallel cam surface on the far side terminating before the parallel cam surface on the near side closing the jaw of the far grippers before the near grippers to support the far edge of a bag top while the near edge is placed in the near grippers, and a continuous chain conveyor for moving the frame past the stationary cams and beneath the cleaning tube.

6. In a bag cleaning machine, a cleaning tube for drawing foreign matter from a bag, an open frame through which a bag may pass having grippers on the near and on the far side for gripping the open top of a bag to be cleaned, said grippers having a fixed jaw and a movable jaw resiliently urged toward the fixed jaw, stationary cams extending beside the path of travel of the near and far side of the frame being contacted by the movable jaws and opening them

as the frame is moved past, the far jaws losing contact with the cam before the near jaws to close the far jaws to grip and support the far edge of the bag while the near edge is placed in the near grippers, and a continuous chain conveyor for moving the frame past the stationary cams and beneath the cleaning tube.

7. In a bag cleaning machine, a tube maintained under a partial vacuum and open at the lower end, a second similar tube, a conveyor moving in a direction from the opening of the first tube to the opening of the second tube, an open frame through which a bag may pass carried by the conveyor past the tube openings and having grippers thereon for gripping the open top of a bag to be cleaned, the depending bag being drawn through the open frame and into the tube thereby turning the bag inside out as the frame passes beneath the tube opening, said frame being centrally pivoted at its sides on the conveyor so that the frame rotates through half a revolution as the conveyor moves from the first to the second tube and the bag is drawn from the tube and falls to again depend from the frame, the bag being similarly drawn into and out of the second tube as the conveyor passes the frame past the opening.
